UNITED STATES PATENT OFFICE

CARRIE S. HOPWOOD, OF HINSDALE, MONTANA

WORKHOLDER

Application filed June 18, 1928. Serial No. 286,233.

This invention relates to new and useful improvements in work holders adapted to be used by seamstresses and others who do needle work, the main object of the invention being to provide a holder of this character which may be readily clamped to the arm of a chair, to the table of a sewing machine or to any other convenient place and to which the work may be attached in order that it may be held taut by drawing upon the goods with one hand leaving the other hand free to use a needle, a stitch ripping tool or a pair of scissors.

With the foregoing and other objects in view as the nature of the invention will be better understood, the same comprises the novel form, combination and arrangement of parts hereinafter more fully described, shown in the accompanying drawings and claimed.

In the drawings wherein like reference characters indicate corresponding parts throughout the several views:—

Figure 1 is a side elevation of my improved work holder as actually attached to the table of a sewing machine or to any other work table.

Figure 2 is a top plan view thereof.

Figure 3 is a rear end elevation.

Figure 4 is a longitudinal vertical cross section the holder being in open position to permit the work to be attached thereto.

Figure 5 is a detail vertical section taken through the holder when in closed condition and substantially upon the line 5—5 of Figure 1.

Figure 6 is a perspective of the main body member of the table or chair arm clamp.

Figure 7 is a perspective of one of the rubber blocks associated with the opposed faces of the clamp plates for engagement with the work so as to prevent the tearing thereof.

Now having particular reference to the drawings, my novel work holder consists of a table or arm chair engaging unit consisting of a body member 5 of suitable metal and of substantially U-formation as illustrated in Figures 4 and 6 one longitudinal wall thereof being longer than the other said longer wall

adapted for engagement upon the top side of a table A or upon the top side of the arm of a chair or other suitable support, the lower shorter leg having a threaded opening 6 therethrough to which is threaded a clamping bolt 7 the inner end thereof having a swivel cushion head 8 for engagement with the under side of the table or arm chair whereby said unit is rigidly secured thereto.

Intermediate the end of the upper longer wall of this member 5 there is formed at the edges thereof upstanding flanges 9—9 between the forward ends of which is arranged a cushion block or plate 10. For cooperation with this unit and especially the upper wall thereof to provide a work clamp there is arranged upon the top side thereof an L-shaped clamp jaw 11 between the innermost ends of which is arranged a transverse coil spring 12 the end convolutes of which are extended forwardly to provide arms 13—13 the ends of which are bent inwardly for engagement within openings in the adjacent flange 9 of the member 5 as well as the adjacent one of similar downturned flanges 14—14 in the horizontal wall of the L-shaped clamp 11 the vertical wall thereof providing a handle whereby this jaw may be opened or closed with respect to the complementary jaw of the table engaging clamp member 5.

It will thus be seen that I have provided a novel, simple and highly useful work holder that is well adapted for all of the purposes heretofore designated and even though I have herein shown and described the invention as consisting of certain detail structural elements it is nevertheless to be understood that some changes may be made therein without affecting the spirit and scope of the appended claim.

Having thus described my invention, what I claim is:—

A work clamp comprising a pair of superposed flat jaw members, an upstanding arm formed on the rear end of the upper jaw member, a depending arm formed on the forward end of the lower jaw member, an inwardly extending leg on said arm arranged in parallel relation to the lower jaw, a clamp bolt carried by said leg, longitudinally ex-

tending flanges formed on the side edges of the jaw members, a transversely extending coil spring arranged between said jaw members having arms formed on the opposite ends thereof anchored in the opposite flanges of said members, and flat cushion jaw faces carried by the jaw members and confined between said flanges.

In testimony whereof I affix my signature.

10

CARRIE S. HOPWOOD.
